CATHODE-RAY IGNITION ANALYZER

Peter S. Christaldi, Wood-Ridge, N. J., assignor
to Allen B. DuMont Laboratories, Inc., Passaic,
N. J., a corporation of Delaware

Application September 29, 1942, Serial No. 460,142

19 Claims. (Cl. 171—95)

This invention is for a device or system that is particularly useful for analyzing the spark plug ignitions of internal combustion motors, such as aircraft engines, for example, by applying signals from the spark plugs to cathode-ray tubes through circuits that amplify the signals and so relate them that signals from any spark plug can be identified and enlarged so as to be readily examined visually without loss of time.

Heretofore the investigation of spark plugs on airplane engines has in many cases required removal of complicated ignition shielding systems around the spark plugs as well as removal of the spark plugs themselves.

By the present invention the individual spark plugs can be tested without removing them or their shields, and different sorts of defects can be ascertained in the ignition system, such as cracked spark plugs, faulty air gaps, poor insulation or short circuits, load conditions of engine, valve adjustments and richness of fuel, etc.

In carrying out the invention, only a single circuit connection is required from this device to the ignition system to be tested. Signals from all spark plugs operating from one magneto can be viewed at one time on a cathode-ray tube, and any spark plug which appears to be abnormal can be selected and shown on an enlarged scale where it can be examined in more detail. At the same time its signal can be intensified on the small scale for certainty of identification when it is being examined on the large scale.

Briefly, the principle upon which the invention operates is that a sawtooth signal is generated and synchronized to provide a sawtooth sweep for each revolution of the accessory or distributor shaft of the engine of which the spark plugs are to be tested. This sawtooth sweep is applied to the horizontal deflection plates or coils of a cathode-ray tube to provide a horizontal time base. At the same time, signals from the magneto, consisting of discharges from all of the spark plugs in the sequence of their firing order, are applied to the vertical deflecting plates or coils of this cathode-ray tube so that the spark plug discharges are all shown on a small scale as they occur in sequence in the engine.

Since all the spark plugs discharge during the rise in voltage of each sawtooth interval, each spark plug discharges within an interval of time represented by the time of one sawtooth divided by the number of spark plugs. Any one of the discharges or signals can be selected at its proper interval and utilized for control and identification purposes in the system, as will be explained in more detail later.

Another cathode-ray tube is provided with a sweep circuit so timed that the electron beam sweeps across horizontally during a time interval equal or approximately equal to a single discharge of a spark plug, and can be synchronized to the interval of any spark plug of the series.

At the same time a signal of the desired spark plug is applied to the vertical deflecting plates of this tube so that the signal can be more closely examined, while the corresponding signal on the other tube is simultaneously intensified for identification purposes.

The invention may be understood from the description in connection with the accompanying drawings, in which:

Figs. 1a and 1b are end views of cathode-ray tubes showing, respectively, a signal from one spark plug on an expanded time scale and all the signals from all the spark plugs operating from one magneto of an internal combustion engine, on a compressed time scale;

Fig. 2 is a block diagram illustrating an embodiment of the invention. The blocks are correspondingly indicated on the detail drawings;

Fig. 3 is a circuit diagram of connections to the cathode-ray tube 1;

Fig. 4 is a diagram showing a recurrent sweep circuit and amplifier for the cathode-ray tube 2;

Fig. 5 is a diagram of connections for generating control voltages for the cathode-ray tube; and

Fig. 6 shows different wave forms used.

In the drawings, reference characters 1 and 2 indicate cathode-ray tubes of a well known sort which have vertical deflecting plates 3 and 4, horizontal deflecting plates 5 and 6, and grids 7 and 8, respectively.

A lead 10 extends from the distributor D for spark plugs of an internal combustion engine which is represented as having eighteen spark 35 plugs, although engines of different numbers of spark plugs as well as other recurrent phenomena can be tested.

In the block diagram shown in Fig. 2, the lead 10 is shown connected to a vertical amplifier 11 for the tube 1 and a vertical amplifier 12 for the tube 2 and an optional device 13 which is adapted to produce a recurrent sweep signal for the tube 1. Amplifiers 14 and 15 are shown diagrammatically in Fig. 2 for the horizontal deflecting

45 plates 5 and 6, respectively. A horizontal sweep sawtooth generator 16 is synchronized by signals from a contactor driven by the auxiliary shaft of the internal combustion motor. This sawtooth generator is connected to the horizontal amplifier 15 and also to the Z-wave cathode-ray

50 intensity modulating waves (Figs. 2 and 5), shaping circuits of block diagram 17, from which a lead extends to the differentiating and squaring unit 18 that may be connected to the grids 7 and 8 of the cathode-ray tubes 1 and 2, respectively. This squaring unit 18 is also connected to the single sweep circuit 19. A switch 20 is provided to make contact between the horizontal amplifier 14 and the recurrent sweep 13 or im-

60 pulse sweep 19 at will. A switch 20a is provided in the connection from the unit 18 to the grids 7 and 8. It is ganged with switch 20.

In Fig. 3 the vertical amplifier 11 of Fig. 2 is shown with the lead 18 which is from the distributor D. It is connected by blocking condenser 22 to the first grid of the duplex triode amplifier 23, and the usual grid leak 24 is provided. The amplified signal for one of the plates 3 of the cathode-ray tube 1 is taken off of the first plate of the diode 23 by means of the lead 25, and the other signal in phase opposition is taken off of the other plate by means of the lead 26. The vertical positioning resistance 27 is provided as a source of positioning potential.

The horizontal amplifier 14 of Fig. 2 is also shown in Fig. 3 with the switch 28 by which it may be connected to either one of the two horizontal sweep generators 13 or 18 of Fig. 2 for the cathode-ray tube 1. The switch 28 is connected to the grid 30 of an amplifier tube 31 of which the cathode is loaded to constitute an impedance transformer. The signal from this cathode is applied by a coupling capacitor, a gain control resistor, and lead 32 to a grid of the duplex triode amplifier 23 that is similar to the duplex triode amplifier 22. Tube 23 is connected to the horizontal deflecting plates 5 of the tube 1 in a similar way to supply the amplified sweep signal to these plates from the generator 13 or 18, depending upon the position of the switch 28.

When the switch 28 is moved to connect the grid 30 with the terminal 35' of the lead 35, the horizontal plates 5 of the tube 1 are connected to the single sweep circuit 19 of Fig. 2, the diagram of connection for which is shown in Fig. 3. This circuit is made up of charging capacitors 39 and 42, as selected by switch 41, charging resistors 37 and 37', gas triode 44, diode 44', and potential divider 40. With diode 44' eliminated from the circuit, the gas triode 44 and its associated components operate as a generator of recurrent sawtooth waves in a manner well known. When the diode 44' is placed in the circuit and the potential is adjusted at 37' until, in the absence of signals at the grid of tube 44, oscillations cease, the application of a positive pulse to the grid of tube 44 will result in the generation of a single linear sweep of the linear time base. When switch 41 is connected to capacitor 39, signals of lower frequency are generated than when it is connected to capacitor 42. In the former condition, switch 41a which is ganged with switch 41 makes connection to capacitor C18, in order that lower frequency signals can be coupled from tube 85a to the grid of gas triode 44 to permit positive initiation of single linear sweeps. The details of tube 85a are further explained in connection with Fig. 5.

When the switch 28 is turned to the terminal 35', a recurrent sawtooth wave is applied to the horizontal deflection plates 5 of the cathode-ray tube 1, to provide a linear time base of sufficiently high frequency to permit the superposition of the individual spark plug discharges for purposes of comparison. This sawtooth wave is generated in the recurrent sweep generator 18 of Fig. 2, which is shown in more detail in Fig. 3. It consists of the gas triode 88, charging capacitors 81 which can be cut in by switch 81' and charging resistors 82, potentiometer 83 for the control of amplitude of synchronizing signal, and coupling capacitor 84 through which can be applied to the grid of tube 88 signals for synchronizing the sawtooth oscillations.

The block 12 in Fig. 2 indicates the amplifier for the signals that are to be applied to the vertical deflection plates 4 of cathode-ray tube 2,

It is similar to the amplifier 11 in Fig. 3, and the same input signals are amplified by it.

The diagram of connections for the horizontal sweep sawtooth generator 18 of Fig. 2 which generates a recurrent sweep signal for the cathode-ray tube 2 is shown in Fig. 4 together with the amplifier 15 for this horizontal sweep sawtooth signal. Positive potential is applied through the charging resistors 86, one of which is variable to the plate of the gas filled triode 81, and charging capacitors 82 of different sizes are provided to be connected between the resistors 86 and the cathode, so that sawtooth waves of different frequencies may be generated. This sawtooth wave generator is synchronized by signals from a contactor synchronous with the magneto M, or by signals from the magneto itself, applied through the capacitor 88 with the grid potentiometer 89 connected to ground. This synchronized sawtooth wave is applied through the lead 85 to the grid of the amplifier 86, which has a loaded cathode 87, thus providing an impedance transformer. A lead 88 connects from this cathode through a capacitor 89 and potentiometer 89' to the first grid of the duplex triode 78 of which the cathodes are connected together so that the plates thereof will deliver sawtooth-wave shaped voltages in phase opposition to the respective horizontal deflecting plates of the cathode-ray tube 2 in the usual way.

The sawtooth wave generated in the recurrent sweep circuit (Fig. 4) is also taken off by the lead 75 and applied to block 17 of Fig. 2, which is shown in detail in Fig. 5. This sawtooth wave is applied to the grid of a triode amplifier 76. The amplified sawtooth signal from the tube 76 is applied through a blocking capacitor 77 to the cathode follower impedance transformer 78, having a positive grid bias supplied by potential divider 79. This signal is applied through the lead 80 to a diode clipper 81 to produce a so-called Z-wave which may modulate the intensity of the cathode-ray beam of tubes 1 and 2. It will be more completely described later. This Z-wave is amplified by being applied through the blocking capacitor 83 to the grid of the tube 84 which is provided with a grid leak 85. The amplified signal then passes through the short-time-constant coupling network made up of capacitor 86 or 88 and 88' in parallel, chosen by switch 41C, and resistors 87 and 87' in parallel. Diode 88 is a surge limiter to prevent the passage of negative polarity surges. The differentiated signal is then applied to the grid of the cathode follower tube 89 and thence passes to the clipping tube 90. It is then passed through a capacitor 91 to a squaring clipper 92 from which the squared signal is taken off to the grids of the cathode-ray tubes 1 and 2 by means of the lead 93.

The operation of the device will be described in detail where it is used to test the spark plugs of an internal combustion engine having eighteen spark plugs, energized from a common magneto, that is provided with the usual auxiliary shaft that revolves once during the interval in which all of the spark plugs fire. This auxiliary shaft is provided with a pin that makes contact once per revolution to produce a signal 105 (Fig. 6a) each revolution. This would be ten signals per second, for example, with an engine auxiliary shaft running 600 R. P. M.

These signals 105 are applied to the sawtooth generator 18 (Fig. 2), which means applying it to the grid of the tube 81 (Fig. 4) to synchronize

the generation of the sawtooth wave (Fig. 6b). The wave forms of Fig. 6 are shown in a manner to illustrate the several steps of wave shaping. The polarities of some of the waves shown may, in the operating circuit, be inverted from those shown in Fig. 6. The wave of Fig. 6 is amplified by the amplifier 15 (Fig. 2), which comprises amplifiers 66 and 70 (Fig. 4), and is applied to the horizontal deflecting plates of cathode-ray tube 2. At the same time, signals from the terminals of the distributor D (Fig. 2) for all the spark plugs are applied in sequence during each sweep interval to the vertical deflection plates 4 of the cathode-ray tube 2 after having been amplified by the amplifier 12 (Fig. 2) which is similar to the amplifier 14 shown in Fig. 3. This gives a visual indication such as is shown in Fig. 1b and Fig. 6f, the showing in Fig. 6f being spaced wider and on a smaller vertical scale than that in Fig. 1b. Simultaneously, the vertical deflection signal is amplified by the amplifier 11 and applied to the vertical deflection plates 3 of cathode-ray tube 1.

The sawtooth signal (Fig. 6b) is at the same time passed through shaping circuits 17 and differentiating circuits 18 (Figs. 2 and 5) and applied to the grids of the cathode-ray tubes 1 and 2. In order to do this the signals are taken off by means of lead 75 (Fig. 4) and amplified by the tube 76 (Fig. 5) thus producing a sawtooth wave like Fig. 6b, but amplified. The tube 76 is used to provide a low impedance signal source to feed the clipper 81. A so-called Z-wave is produced as shown by Fig. 6d by clipping the wave (Fig. 6b) with the wave clipper 81 (Fig. 5) that will be described in detail below. It is clipped at a potential corresponding to the lower dotted line b' of Fig. 6b to give the wave (Fig. 6c) and at a potential corresponding to the upper dotted line b'' of Fig. 6b to give the wave (Fig. 6d). This wave is amplified by the amplifier 84 (Fig. 5) to give the wave (Fig. 6e). The wave (Fig. 6e) is then differentiated by means of the capacitors 86 and 86' and the resistors 87 and 87' and limited in negative amplitude by the diode 88 (Fig. 5) to give the wave (Fig. 6f) which is squared at tube 90 and amplified at 92 to give the wave (Fig. 6g). This wave, (Fig. 6g), is then passed through switch 20a to the grid 1 of the cathode-ray tube 1 and is also attenuated and passed to the grid 8 of the cathode-ray tube 2 (Fig. 2). In this way that portion of the vertical signal wave which occurs during the time interval corresponding to the impulse wave of Fig. 6g will be made brighter than other parts of the sweep cycle. This makes it possible for the observer to identify on cathode-ray tube 2 any particular spark plug that is being examined in expanded time scale on cathode-ray tube 1, as explained below. The particular spark plug is that one the firing time of which corresponds to the interval in the cycle represented by the wave of Fig. 6g.

For example, the spark plug impulses of Fig. 6j show the 16th spark impulse intensified, with enough of the previous and the following pulses shown to allow a complete record of the 16th pulse, as examined in more detail on the expanded scale of cathode-ray tube 1, Fig. 1a.

The wave clipper mentioned above is shown in Fig. 5. It comprises a potentiometer 98 with two sets of taps 99 and 100 and with the coupled movable contactors 101 and 102 connected, respectively, to the cathode load resistor of the duplex diode 81, and to the anode return resistor 104 of

the last or right-hand plate thereof. The location of the contactor 102 on a tap 100 determines the potential level location of the lower dotted line b' on Fig. 6b, and the location of the contactor 101 on a tap 99 determines the potential level of the upper dotted line b'' on Fig. 6b. Thus by shifting the contacts 101 and 102 any segment 103 (Fig. 6d) can be clipped out of the wave (Fig. 6b) corresponding to any one of the spark plugs, so that the signal (Fig. 6g) finally obtained from (Fig. 6d) when applied to the grid of cathode-ray tube 2 will make the signal of the plug under examination brighter than the others, and when applied to the grid of cathode-ray tube 1 will make the corresponding signal thereon clearly visible.

The circuit of Fig. 5 shows facilities for examining eighteen spark plugs. In practice, the equipment is made more flexible in order to divide the sweep interval into several numbers of segments. For example for testing 8 spark plugs, or other recurrent signals, the voltage divider 98 may be tapped at any suitable intermediate point rather than at the end and a heavier current passed through the divider. In this way the wave form (Fig. 6b) is divided into 8 equal steps instead of 18. A continuously adjustable potentiometer may be used, since the brightening by grid signal identifies the selected interval.

The wave form of Fig. 6g is passed through the impedance transformer 95a (Figs. 3 and 5) and is differentiated by means of capacitors C15 and C16 and resistor 44' to produce the synchronizing pulse 106 (Fig. 6h), which pulse 106 is then fed to the single sweep sawtooth wave generator 19 (Figs. 2 and 3) to yield the spreading wave form (Fig. 6i), which is amplified by the amplifier 14 (Figs. 2 and 3) when the switch 20 contacts are at 35', and is applied to the horizontal plates 5 of the cathode-ray tube 1.

The switches 41 (Fig. 3), 41a (Figs. 3 and 5), and 41c (Fig. 5) are connected mechanically as indicated by dotted line e in any convenient way so that when the switch 41 connects the larger capacitor 39 in the circuit the switch 41a connects the capacitor C16 in parallel with the capacitor C15 and the switch 41c connects the capacitor 86 in parallel with the capacitor 86'. In this condition the wave form (Fig. 6g) is differentiated to give the synchronizing pulse (Fig. 6h) which is of variable phase with respect to the pulse 105 (Fig. 6a) so that the sweep signal (Fig. 6i) for tube 1 is applied to the horizontal deflecting plates 5 during the interval when the signal from the spark plug being tested is applied to its vertical deflecting plates 3. The switches 20 (Figs. 2 and 3) and 20a (Figs. 2 and 5) are also mechanically connected as indicated by dotted line o so that when the amplifier 14 is connected to the sweep 19 (Figs. 2 and 3) by switch 20, the switch 20a closes the circuit to apply the signal (Fig. 6g) from the differentiating and squaring unit 18 (Figs. 2 and 5) to the grids of cathode-ray tubes 1 and 2. When the switch 20 closes the circuit to apply the recurrent sweep from generator 13 (Figs. 2 and 3) to the plates 5 of tube 1, the switch 20a (Figs. 2 and 5) opens the circuit to the grids 1 and 8 and grounds them.

Although this invention has been particularly described in connection with the test and examination of spark plugs for internal combustion engines, it is also applicable for investigations wherever the phase of one sweep circuit is to be changed with respect to another one or with respect to other recurrent phenomena that are to

be investigated, and where it is desired to indicate on an expanded time scale, or otherwise to modify, the phenomena occurring during a particular interval of a cycle.

What is claimed is:

1. An analyzer comprising two cathode-ray tubes, x -axis and y -axis deflecting means for the rays of said tubes, and means to render a series of signals visible on one of said cathode-ray tubes and means to render one of the same signals simultaneously visible on a larger scale on the other cathode-ray tube.
2. An analyzer comprising two cathode-ray tubes, x -axis and y -axis deflecting means for the rays of said tubes, and means to render a series of recurrent signals from different sources visible on one of said cathode-ray tubes and means to render one of the same signals simultaneously visible on a larger scale on the other cathode-ray tube.
3. The analyzer of claim 1, in which means is provided to render at will any one of the series of signals visible on the other cathode-ray tube.
4. An analyzer comprising two cathode-ray tubes, x -axis and y -axis deflecting means for the rays of said tubes, means to render a series of signals visible on one of said cathode-ray tubes and means to render one of the same signals simultaneously visible on a larger scale on the other cathode-ray tube, and means to identify one of the small scale signals as the one that is on the other cathode-ray tube.
5. An analyzer comprising two cathode-ray tubes, x -axis and y -axis deflecting means for the rays of said tubes, means to render a series of signals visible on one of said cathode-ray tubes and means to render one of the same signals simultaneously visible on a larger scale on the other cathode-ray tube, and means for causing the sweep signal for the larger scale cathode-ray tube to occur at the frequency which is a fraction of the frequency of the signals on the other one.
6. An analyzer comprising two cathode-ray tubes, x -axis and y -axis deflecting means for the rays of said tubes, means to render a series of signals visible on one of said cathode-ray tubes and means to render one of the same signals simultaneously visible on a larger scale on the other cathode-ray tube, and means for synchronizing the sweep signals on both cathode-ray tubes.
7. An analyzer comprising two cathode-ray tubes, x -axis and y -axis deflecting means for the rays of said tubes, means to render a series of signals visible on one of said cathode-ray tubes and means to render one of the same signals simultaneously visible on a larger scale on the other cathode-ray tube, and means to identify one of the small scale signals as the one that is on the other cathode-ray tube, said last named means comprising selective grid control of said other cathode-ray tube.
8. An ignition analyzer for an internal combustion engine, which comprises two cathode-ray tubes, x -axis and y -axis deflecting means for the rays of said tubes, and means to render signals from all the spark plugs visible on one of said cathode-ray tubes and means to render one of the said signals visible simultaneously on a larger scale on the other cathode-ray tube.
9. The analyzer of claim 8, in which means are provided to render any one of the signals visible on said larger scale cathode-ray tube.
10. The analyzer of claim 8, in which the sweep circuits of the cathode-ray tubes are synchronized in accordance with said signals.
11. The analyzer of claim 8, in which the horizontal sweeps of said cathode-ray tubes are synchronized by a signal from an auxiliary shaft of said engine.
12. The analyzer of claim 8, in which the signals applied to the vertical deflection plates of said cathode-ray tubes are derived from the spark plugs of said engine.
13. The analyzer of claim 8, in which the signals applied to the vertical deflection plates of said cathode-ray tubes are derived from the spark plugs of said engine and the recurrence of the respective sweep signals of said cathode-ray tubes is proportional to the number of spark plugs being tested.
14. An ignition analyzer for an internal combustion engine, which comprises two cathode-ray tubes, x -axis and z -axis deflecting means for the rays of said tubes, and means to render signals from all the spark plugs visible on one of said cathode-ray tubes and means to render one of said signals simultaneously visible on a larger scale on the other cathode-ray tube, said means comprising a square impulse generator.
15. An ignition analyzer for an internal combustion engine, which comprises two cathode-ray tubes, x -axis and z -axis deflecting means for the rays of said tubes, means to render signals from all the spark plugs visible on one of said cathode-ray tubes and means to render one of said signals simultaneously visible on a larger scale on the other cathode-ray tube, said means comprising a square impulse generator, and means to apply said impulse to the grid of one of said cathode-ray tubes.
16. The analyzer of claim 8, in which means is provided to produce a synchronizing pulse of variable phase and apply it to the sweep signal generator of one of said cathode-ray tubes.
17. An ignition analyzer for an internal combustion engine, which comprises two cathode-ray tubes, x -axis and z -axis deflecting means for the rays of said tubes, means to render signals from all the spark plugs visible on one of said cathode-ray tubes and means to render one of said signals simultaneously visible on a larger scale on the other cathode-ray tube, and means for optionally applying a single sweep to one of said cathode-ray tubes during discharge of a set of spark plugs or applying recurrent sweeps to it corresponding to each spark plug discharge.
18. In a device of the character described, a potentiometer having two sets of fixed contacts and two coupled contactors for said sets of contacts movable to different contacting positions for contacting respectively with said sets of contacts, means for generating a sawtooth wave and feeding it simultaneously to said potentiometer at two distinct potential levels on said potentiometer for fixed positions.
19. In a device of the character described, means to produce a sawtooth wave at a desired frequency, clipping means for said wave comprising a potentiometer having sets of contacts and coupled contactors, a vacuum tube to the plate and cathode of which said sets of contactors are connected respectively to clip said wave at distinct levels for various positions of said contactors and produce pulses simultaneously at predetermined phases with respect to said wave, an oscilloscope, and means to apply said pulses to the control grid of said oscilloscope.
